UNITED STATES PATENT OFFICE.

CHARLES H. BRADLEY AND FRANK D. ALLEN, OF CLEVELAND, OHIO.

SEPARABLE FASTENER.

Application filed March 27, 1924. Serial No. 702,215.

To all whom it may concern:

Be it known that we, CHARLES H. BRADLEY and FRANK D. ALLEN, citizens of the United States, residing at Cleveland, in the county of Cuyahoga and State of Ohio, have invented certain new and useful Improvements in Separable Fasteners, of which the following is a specification.

Our invention relates to improvements in separable fasteners, the present embodiment of the invention being in the specific form of a separable cuff button or link for use in fastening together cuffs and wherein the cuff buttons remain in the buttonholes when the parts are separated in order to open or unfasten the cuff.

The primary object of the invention is to provide a generally improved separable or two-part fastener of the type indicated, which will be exceedingly simple in construction, cheap of manufacture, and efficient in use.

A further and important object is the provision of a cuff connecting link or button of this class in which the connecting parts are concealed and protected while in use when the mating parts are in their connected position and in which the coupling or latching mechanism is operated solely by relative rotation or movement of the button members while in the cuff.

A further and very important object is the provision of a fastener of this type in which the parts are positively locked when in their connected position and are positively unlocked when the coupling members or buttons are moved to an unlocked position relative to each other.

A still further object is the provision of a separable cuff button of improved form better adapted to be retained within and secure the cuff when connected, as well as adapted to permit of relative movement to each other when it is desired to connect or disconnect the same.

With the above mentioned and other ends in view, the invention consists in the novel construction, arrangement and combination of parts, hereinafter described, illustrated in one of its embodiments in the accompanying drawings, and particularly pointed out in the appended claims.

Referring to the drawings, forming a part of this specification, Figure 1 is an enlarged side elevation of a two-part separable cuff

button, constructed in accordance with this invention, the parts being in connected or locked position.

Fig. 2, a fragmentary sectional view taken on line 2—2 of Fig. 1. 60

Fig. 3, a similar view with the right hand button turned at right angles or a quarter turn to the other, thereby releasing the spring or locking elements from the slots or recesses in the stud or head member of the second button member to release the latter. 65

Fig. 4, a transverse sectional view, taken on line 4—4 of Fig. 2. 70

Fig. 5, a plan or face view of the inner or stud side of the separable button. 75

Fig. 6, a similar view of the socket carrying button member, illustrating in particular the locking or latching elements movable toward and from each other in the socket. 75

Similar numerals of reference designate like parts throughout all the figures of the drawings.

The improved separable fastener when in the specific form of a separable cuff button comprises button members 1, of any suitable and convenient form, said button members being provided with shank portions 1^a, preferably of round hollow form, as shown, and terminating in relatively flat base members 1^b. The inner or adjacent sides of the shanks 1^a are preferably of flaring or bell shape, as at 1^c, such shape forming a convenient inner cavity for the semi-spherical shaped socket 1^d, of the base plates 1^b, the latter being secured to the edges of the bell portions of the shanks by means of overturned flanges 1^e. 80 85 90 95

The resilient latching or fastening elements 2^a, are preferably in the specific form of spring actuated bars 2^a extending parallel and, in the present instance, comprising the terminal portions of a single length of wire bent into a base loop 2, the latter being seated in the annular outer space between the terminal portions of the bell 1^c and the base plate 1^b provided with the socket 1^d. 100

The parallel extending spring actuated bars or latching members 2^a operate in oppositely arranged slots 1^f, at the sides of the socket 1^d, as shown most clearly in Fig. 4 of the drawings. The head or stud member 1^g, of the opposing or companion button is provided on two sides with slots 1^h, adapted to receive and interlock with the latching elements or bars 2^a when the two buttons are 110

in registration or normal connected position, as shown in Figs. 1 and 2 of the drawings, and in such connected or locked position no amount of force will separate the head and socket members from each other.

As a means of manually causing the locking or latching elements 2^a to be forced out of the slots 1^b upon a relative movement of the buttons, as for example the rotation or 10 movement of the second button at right angles to the other, or a quarter turn, and particularly as a means of causing the spring action of such locking elements or arms 2^a to contact with the inclined wedge-shaped 15 portions of the stud 1^c, as hereinafter referred to, to force the two buttons apart, two oppositely arranged or inclined relatively flat portions 1ⁱ, are formed intermediate the bar receiving slots or recesses 1^b 20 so that when the buttons are twisted a quarter turn relative to each other, as shown in Fig. 3, the bars 2 will ride out of the slots 1^b and coming into contact with the inclined or wedge-shaped portions 1ⁱ will eject the 25 buttons to a disconnected position.

As a means of causing the two locking or latching elements 2^a to expand or ride over the stud portion when the buttons are in registration and are pressed together, two 30 more abrupt inclined or flanged portions 1^j, are formed intermediate the relatively flat wedge-shaped portions 1ⁱ, said rounded portions 1^j terminating at their base portions in slots 1^b and forming a nose portion 1^k 35 to enter between the bars 2^a when the buttons are in registration and pressed together.

As a means of conveniently indicating the relative positions of the button members with respect to the locking and unlocking 40 positions thereof, the button and base portions are preferably of elongated or irregular form, as shown, this form also more securely holding the buttons in position in the button-holes of the cuff.

Having thus described one of the embodiments of our invention, without having attempted to set forth all the forms in which it may be made, or all the modes of its use, what we claim and desire to secure by Letters Patent is,—

1. A separable cuff button comprising button members provided with hollow bell-shaped shanks and mating base portions including stud and socket members, said socket members being provided with oppositely arranged spring latching elements movable toward and from each other in said socket and said stud member being provided with inclined sides and intermediate rounded flanges having latch receiving recesses.

2. In a separable fastener, including separable members having head and socket members, said members being provided with spring locking elements and said head member having wedge-shaped sides adapted to

enter and expand said latching members and terminating in intermediate latch receiving recesses receiving said latching members when in one position, and when moved circumferentially disengaging said latching 70 elements.

3. A separable fastener, comprising members provided with hollow bell-shaped shanks and abutting base portions including stud and socket portions, said socket 75 being provided at its base with oppositely arranged resilient latch bars movable toward and from each other therein, and said stud being provided with wedge-shaped 80 sides and intermediate rounded portions having latch bar receiving recesses intersecting the base portions of said wedge-shaped sides.

4. A separable cuff button, comprising mating buttons including head and socket 85 members, said socket member being provided at its sides with opposite fastening elements movable towards and from each other and said head member being provided with a wedge-shaped portion adapted in one position to expand said fastening elements and having base slots receiving said fastening elements when in one position and expanding and ejecting said fastening elements when moved to another position.

5. A separable cuff button, comprising mating buttons provided with head and socket members, said socket member being provided with resilient fastening elements 90 movable toward and from each other, and said head member being provided with opposite flattened portions adapted to enter between and expand said resilient fastening elements and provided with intermediate slots at the base portions thereof adapted to receive said fastening elements when moved to a predetermined position and to expand and eject said fastening elements when moved a quarter turn.

6. In a separable fastener, including separable members having head and socket portions, said socket portion being provided with oppositely arranged spring latching members and said head member being provided with wedge-shaped sides adapted to enter and expand said latching members and terminating at their base portions in intermediate latch receiving recesses to receive said latching members when moved to a predetermined position, and when moved a quarter turn disengaging said latching members from said recesses and expanding the button members by the coaction of said latch members on said wedge-shaped sides.

7. A separable cuff link, comprising mating member provided with base portions adapted to abut against each other and having hollow socket and stud members, resilient latching members movable toward and from each other in said socket member, said

stud member being provided with oppositely arranged inclined sides and intermediate rounded portions terminating in latch receiving recesses opposite said inclined sides whereby in one predetermined position said resilient latching members are moved apart and when the buttons are brought together

in registration said recesses will be engaged by said resilient latching members.

In testimony whereof we have affixed our ¹⁰ signatures.

CHARLES H. BRADLEY.
FRANK D. ALLEN.
